LOCKING BOTTLE CAP

William B. Rosevear, Jr., Birmingham, Mich., assignor to Benjamin H. Anibal, Birmingham, Mich.

Application May 27, 1938, Serial No. 210,473

14 Claims. (Cl. 215—98)

The invention relates to closures for bottles or the like, and it has particular relation to a closure which may be releasably locked on the bottle.

In certain instances it is desirable to have a closure or cap which may be releasably locked on a bottle in such manner that normally only an authorized person will be able to remove the cap and thus gain access to the contents of the bottle. As a specific instance, it is desirable to use a lockable closure of this character in liquor dispensing establishments where as a rule many partly filled bottles are always on hand. By preventing access to the bottles in this manner, substantial loss will thus be prevented, and this is particularly true in connection with bottles of liquor owing to the cost thereof.

One object of the present invention is to provide a lockable closure for bottles which is inexpensive in construction and which is characterized by a simplicity of operation.

Another object of the invention is to provide a lockable closure such as designated, which involves a combination lock that is easy to manipulate to the end that a minimum amount of effort and time will be required to lock and unlock the closure.

Another object of the invention is to provide a lockable closure as mentioned wherein a combination lock is provided which is so designed and constructed that the combination may be varied very easily.

Another object of the invention is to provide a lockable closure of the aforesaid character which is so designed and arranged that even though an unauthorized person learns of the combination, a normally unknown and particular manipulation would be required before the closure could be unlocked.

Other objects of the invention will become apparent from the following specification, the drawing relating thereto, and from the claims herein-after set forth.

For a better understanding of the invention, reference may be had to the drawing, wherein:

Figure 1 is a fragmentary elevational view of a bottle having a lockable closure constructed according to one form of the invention, with certain parts of the arrangement shown in cross-section;

Fig. 2 is a plan view of the closure shown by Fig. 1, with certain parts broken away and others shown in cross-section for the purpose of illustrating inner parts of the closure;

Fig. 3 is a cross-sectional view taken substantially along the line 3—3 of Fig. 1;

Fig. 4 is a plan view similar to Fig. 2, illustrating the parts operable according to a predetermined combination and set to permit unlocking of the closure; and

Fig. 5 is a detail view illustrating a form of slot which may be used according to another form of the invention.

Referring to Fig. 1, a bottle 10 is illustrated, which has a neck 11 provided with external thread elements 12, such as are ordinarily provided on bottles for fastening caps thereon. A cup shaped bottle cap 13 is provided for the bottle and this cap has spiral grooves 14 on the inner surface of its side wall by means of which the cap may be threadedly engaged with the thread elements 12 on the bottle. Normally a cork disc or other sealing element 15 is provided in the cap for positively sealing the opening in the bottle as will be readily understood. So far the construction described is characteristic of standard bottles and caps therefor, and while the invention has a wider range of application than that of the particular structure illustrated, it will be appreciated that it is applicable to a cap and bottle assembly already widely in use.

The general principle of the invention illustrated is to provide a cover means for the cap that normally will prevent access to the latter, and hence which will normally prevent turning of the cap so as to remove it from the bottle. This cover means generally comprises an annular member 18 normally retained on the cap and rotatable with respect thereto, and a second cup shaped member 20 rotatable with respect to the cap and first member but which may be released from the cap so as to allow access to the latter.

More particularly, the second member 20, while normally rotatable with respect to both the cap 13 and the member 18, is releasable from both the cap and first member when all of such parts are in predetermined and relative circumferential positions. Then the member 20 may be withdrawn axially from the cap, and when so withdrawn, the upper portion of the cap will be exposed so that it may be gripped with the fingers and turned for the purpose of removing it from the bottle.

The member 18 is retained on the cap 13 by means of a split ring 22 disposed partly in annular grooves 23 and 24 in the member and cap, respectively. It will be understood that the ring may be initially disposed in the groove 24 and contracted there sufficiently to allow disposal of

the member 18 in proper position and that then expansion of the ring will cause it to become partly disposed in each groove, thus locking the cap and member together against relative axial movement, while still permitting relative rotation thereof. It will be noted that the member 18 has an inturned flange 26 at its lower end which extends substantially to the bottle surface so as to prevent access to the inner edge face 10 of the cap 13. This flange can be arranged to move between the thread elements 12 on the bottle neck when the cap 13 is turned or it can be terminated a sufficient distance from the bottle neck surface that removal of the cap will not 15 involve any interference between the flange and the thread elements on the bottle neck. At its upper end, the member 18 has an outwardly offset wall portion 30 overlapping the lower end of the side wall of the second member 20 and this 20 overlapping relation eliminates a directly open gap between the members. With the member 18 retained on the cap 13, the manner in which the cap 20 is releasably locked in position is now to be considered.

At its inner side, the outwardly offset portion 30 of member 18 is provided with an annular groove 31, which, as best shown by Fig. 3, communicates at one point with a generally spiral slot 32 that extends from the groove to the upper 30 edge of such offset portion. In radial alignment with the groove 31, a circumferentially arranged series of openings 35 is provided in the side wall of member 20 and these openings are adapted selectively to receive a pin 36. This pin, as shown best by Fig. 1, has a transverse slot in its end disposed in the opening and it is intended that the slotted end be initially expanded so that when pushed into any one opening, it normally will be held in place by its expansion, although it is to be understood that the pin may be removed without undue difficulty.

From this description, it will be seen that upon turning the member 20 and member 18 relatively, the pin 36 may be disposed in alignment with the 45 lower end of slot 32 and that then upon lifting the member 20 and turning it, the pin will move upwardly through the slot, thus permitting removal of such member 20 with respect to the member 18. For the purpose of externally determining the 50 relative positions in which the members 18 and 20 should be disposed to permit such withdrawal of member 20, alphabetical letters are placed on an inclined ledge 37 on member 20 and this ledge incidentally overhangs the upper end face of the 55 offset portion 30 of member 18 so as to prevent anyone from seeing downwardly between the members and observing the position of the pin. Each one of the letters is in vertical alignment with one of the openings 35 and with the parts 60 disassembled, the pin 36 may be disposed in one of the openings and then by noting the letter directly above such opening, one may realize where the pin is located after the parts are assembled.

Adjacent the ledge 37, the offset portion 30 of 65 member 18 is provided with an upstanding, pointed projection or arrow 40 which has a definite predetermined relation with the lower end of slot 32. The lower end of slot 32 might be directly under the arrow 40 within the contemplation of 70 the present invention, and if this were true, assuming that the pin 36 is under the letter A as shown, one would only have to turn the member 20 relative to the member 18 until the letter A became vertically aligned with the arrow 40 and 75 then the pin would be directly at the lower end

of the slot 32 and upward withdrawal of the member 20 relative to member 18 would be permitted. However, in accordance with a further feature of the present invention, it is desirable, as shown, to have the lower end of slot 32 circumferentially offset from the arrow 40 a slight distance, such as half the distance between two letters, so that even if one knew the pin to be under the letter A, for example, he would also have to know that member 20 would have to be so turned 10 that the arrow would be at a point half way between the letters A and B. Thus, if an unauthorized person should learn that the pin 36 is under the letter A, he still would not know that the arrow 40 would have to be half way the distance between the letters A and B before the member 20 15 could be upwardly withdrawn. Inasmuch as one normally would turn a cap counterclockwise in attempting to remove it, it is apparent that even if one unauthorized knew that the pin 36 is under 20 the letter A, counterclockwise turning of the member 20 would move the pin 36 farther and farther from the lower end of the slot 32. Thus, it would quickly appear that the attained knowledge was insufficient. One authorized to know 25 would continue turning the member 20 counterclockwise almost a complete turn and until the arrow 40 is between the letters A and B.

Now referring to Figs. 1 and 3, the upper end of cap 13 has an annular groove 45 in the outer 30 side of its side wall and the inner side of the side wall of member 20 has a circumferentially arranged series of openings 46 similar to the openings 35. A pin 47 similarly is disposed selectively in one of these openings and projects into the 35 groove 45. Groove 45, like groove 31, communicates with a generally spiral slot 48 that extends to the upper end face of the cap 13. An alphabetical series of letters is placed on the upper end face of cap 20, as shown by Figure 2, and with 40 reference to Figs. 1 and 3, this series of letters would extend along the outer surface portion indicated at 50. It will be understood that each letter is in vertical alignment with one of the 45 openings 46.

An arrow 51 is placed on the upper face of the cap 13 and this arrow has the same relation to slot 48 as arrow 40 has with respect to slot 32. Arrow 51 is visible through the upper end wall of the member 20 by having a transparent disc 53 50 inserted in the end wall. This disc may be held assembled with the member 20 by means of a split ring 54 similarly to the manner in which the cap 13 and ring 18 are held together. It will be noted that the metal portion of member 20 extends inwardly towards the center sufficiently to prevent anybody observing through the disc 53 and seeing the pin 47.

Now directing particular attention to Figure 2, it will be observed that the pins 36 and 47 on 60 member 20 are both disposed in openings under the two A letters and the combination is, therefore, A—A. Assuming that the cap is to be removed, the member 20 is turned until the upper letter A is aligned with the arrow 51 and then the member 20 is held in position while the member 18 is turned relative thereto until the arrow 40 is brought into alignment with the lower letter A on ledge 37. It might be stated here that both Figures 2 and 4 indicate the lower and upper end 70 portions of both slots 32 and 48 with the arrows 40 and 51, respectively, between the ends of corresponding slots. So with the two A letters aligned with the arrows 40 and 51, respectively, the pins 36 and 47 are aligned with the two letters, re- 75

spectively, but the lower ends of the two slots are displaced clockwise of the pins a short distance, such as half the distance between two letters. Thus, vertical movement of the member 20 is still prevented. It is necessary to now turn the member 20 while holding the member 18 and bottle against turning, and if turned in a counterclockwise or unscrewing direction, and simultaneously applying upward pulling force, the pins will enter the lower ends of the two slots after almost completing a counterclockwise turn of the member 20. When the two pins enter the lower end of the slots, continued turning will cause the pins to move through the slots until the member is removed. Then the cap 13 may be removed by turning it relative to the bottle.

When the cap is to be replaced on the bottle, it is threaded thereon until tight and then the member 20 is placed over the cap 13 until the pins rest on the upper face of cap 13 and on the upper face of the member 18, respectively. With the parts in this relation, the member 20 is turned until the letter A on the upper face thereof is aligned with the arrow 51 and then the member 18 is turned relative to the member 20 until the arrow 40 is aligned with the lower letter A on ledge 37. Then the member 18 and bottle are held against relative turning, and the member 20 is turned slowly and with slightly downward pressure until the pins drop into the upper ends of the slots 32 and 48. If the member 20 is turned clockwise almost a complete turn to cause the pins to drop into the upper ends of the slots, continued turning of the member in the same direction will cause the pins to finally enter the grooves.

A large number of combinations may be obtained by changing the pins from one opening to another and it is only necessary to remember the letters over the openings in which the two pins are disposed and the relation of the arrows to the slots.

Fig. 5 shows a different form of slot, indicated at 61, which may be employed in place of the slots 32 and 48. In this additional form, the slot has a substantially vertical upper end portion 62 and a generally spiral lower portion. When this type of slot is employed, manipulation of member 20 to move it upwardly brings the pins 36 and 47 into the vertical portions 62 of the slots and when this occurs, the member 20 may be withdrawn by vertically upward movement or if not pulled upward, it may be merely turned, and due to such portions of the slots, the pins will cause unscrewing of cap 13. Thus, in this case, the cap 13 could be removed without actually removing member 20.

In manufacturing the invention, it may be found desirable to initially place the two pins in openings 60 in the upper part of member 20, so as to facilitate assembly of the parts for shipment and so as to eliminate the necessity of the manufacturer recording the combination for each individual bottle. Then it is only necessary for the purchaser of the bottle and contained goods to take the two pins from the openings 60 and place them in selected openings 35 and 46, and the combination thus provided may be changed at will by the purchaser by simply removing the pins from one set of openings and replacing them in another set. Most of the parts of the construction may be manufactured inexpensively in various ways and an inexpensive way of manufacturing such parts is by means of die casting metals 75 suitable for the purpose.

Although only one form of the invention has been illustrated and described in detail, it will be apparent to those skilled in the art that various modifications may be made without departing from the scope of the appended claims. 5

What is claimed is:

1. The combination with a bottle or the like open at one end, of a cup shape bottle cap adapted to fit over said end so as to close the bottle, cooperating means on the inner surface 10 of the side wall of the cap and on the outer surface of the bottle for releasably holding the cap in place and being of such character that turning of the cap relative to the bottle is required in applying and removing the cap, cover means 15 mounted on the cap in enclosing and rotatable relation thereto for normally preventing access to and turning of the latter when it is on the bottle, and including a removable member which when removed allows access to the cap for turning it, and locking means carried by the cap and member for releasably locking the member in cap covering position and which is of such character that unauthorized removal of the cap normally 20 is prevented. 25

2. The combination with a bottle or the like open at one end, of a cup shape bottle cap adapted to fit over said end so as to close the bottle, cooperating means on the inner surface of the side wall of the cap and on the outer surface 30 of the bottle for releasably holding the cap in place and being of such character that turning of the cap relative to the bottle is required in applying and removing the cap, cover means mounted on the cap in enclosing and rotatable 35 relation thereto for normally preventing access to and turning of the latter when it is on the bottle, and including a removable member which when removed allows access to the cap for turning it, and combination locking means carried by the 40 cap and member for releasably locking the member in cap covering position and which is of such character that unauthorized removal of the cap normally 45 is prevented.

3. The combination with a bottle or the like open at one end, of a cup shape cap adapted to fit over said end so as to close the bottle, cooperating means on the inner surface of the side wall of the cap and on the outer surface of the bottle for releasably holding the cap in place and being 50 of such character that turning of the cap relative to the bottle is required in applying and removing the cap, cover means mounted on the cap in enclosing and rotatable relation thereto for normally preventing access to and turning of the 55 latter when it is on the bottle, and including a plurality of annular members, and combination locking means releasably locking one member to an adjacent member and to the cap and being 60 of such character that removal of said one member depends upon disposing the annular members and cap in predetermined positions circumferentially of the cap. 65

4. The combination with a bottle or the like open at one end, of a cup shape cap adapted to fit over said end so as to close the bottle, cooperating means on the inner surface of the side wall of the cap and on the outer surface of the bottle for releasably holding the cap in place and being 70 of such character that turning of the cap relative to the bottle is required in applying and removing the cap, a first annular member on the side wall of the cap at the inner or free edge end of the cap, a second annular member of cup shape fitting over the outer end of the cap in rotatable 75

- relation thereto and jointly with the first annular member providing a cover on the cap for normally preventing access to the latter when it is on the bottle, means holding the first annular member on the cap but permitting relative rotation of the member and cap, means holding the second annular member on the first annular member but permitting their relative rotation, and means holding the second annular member 5
- 10 on the cap but permitting their relative rotation, the last two means being of such character that removal of the second annular member from the cap and from the first annular member depends upon placing the annular members and cap in predetermined circumferential positions relative to one another.
- 15 5. The combination with a bottle or the like open at one end, of a cup shape cap member adapted to fit over said end so as to close the bottle, cooperating means on the inner surface of the side wall of the cap and on the outer surface of the bottle for releasably holding the cap in place and being of such character that turning of the cap relative to the bottle is required in applying and removing the cap, a first annular member 20 on the side wall of the cap at the inner or free edge end of the cap, a second annular member of cup shape fitting over the outer end of the cap and jointly with the first member forming a cover for the cap which normally prevents access to the latter when it is on the bottle, said members having adjacent side wall portions telescoping axially of the cap, means for releasably but rotatably holding the members together 25 including a circumferentially extending groove in one of said side wall portions, a slot extending from said groove to an end of said wall portion and a projection on the other wall portion adapted to move in said groove and slot, and means on side wall portions of the second annular member and cap member for releasably but rotatably holding them together including a circumferentially extending groove in the side wall portion of one member, a slot extending from the groove to an end of the member and a projection on the side wall portion of the other member 30 adapted to move in the groove and slot, the arrangement being such that upon placing all members in predetermined circumferential positions relative to one another, the second member may be removed axially of the cap through relative movement of the projections through the slots.
- 35 6. The combination with a bottle or the like open at one end, of a cup shape cap member adapted to fit over said end so as to close the bottle, cooperating means on the inner surface of the side wall of the cap and on the outer surface of the bottle for releasably holding the cap in place and being of such character that turning of the cap relative to the bottle is required in applying and removing the cap, a pair of relatively rotatable, annular members rotatably mounted on the cap and adapted jointly to enclose the cap so as to normally prevent access thereto when it is on the bottle, means for holding one annular member against axial movement on the cap member but permitting its rotation thereon, and means for holding the other annular member against axial movement on the cap member 40 less such other member and cap member are in predetermined, relative circumferential positions.
- 45 7. The combination with a bottle or the like open at one end, of a cup shape cap adapted to fit over said end so as to close the bottle, cooperating means on the inner surface of the side
- 50 wall of the cap and on the outer surface of the bottle for releasably holding the cap in place and being of such character that turning of the cap relative to the bottle is required in applying and removing the cap, a pair of relatively rotatable 55 annular members rotatably mounted on the cap and adapted jointly to enclose the cap so as to normally prevent access thereto when it is on the bottle, means for holding one member against axial movement on the cap but permitting relative rotation thereof, means on said members for holding the other member against axial movement on the cap unless said members are in predetermined, relative circumferential positions, and means on said other member and on the cap 60 for holding the former against axial movement on the cap unless such second member and cap are in predetermined, relative circumferential positions.
- 65 8. The combination with a bottle or the like open at one end, of a cup shape cap member adapted to fit over said end so as to close the bottle, cooperating means on the inner surface of the side wall of the cap and on the outer surface of the bottle for releasably holding the cap in place and being of such character that turning of the cap relative to the bottle is required in applying and removing the cap, a pair of relatively rotatable annular members rotatably mounted on the cap and adapted jointly to enclose the cap 65 so as to normally prevent access thereto when it is on the bottle, means for holding one member against axial movement on the cap member but permitting its rotation thereon, means for holding the other member against axial movement on the cap member unless such members are in predetermined, relative circumferential positions, and means holding the second member and cap member against relative rotation when the second member is partly moved axially of the cap.
- 70 9. A lockable bottle closure comprising a cup shape cap member adapted to be applied to the bottle, cover means mounted on the cap to rotatable relation thereto and so enclosing the outer surfaces of the cap that when the cap is on the bottle access to the cap is normally prevented, said cover means including a pair of annular members rotatable relatively, means between one of said annular members and the cap for normally holding them together against relative movement axially of the cap, and means concealed by the cover means when assembled with the cap for preventing axial movement of the second annular member relative to the cap except when said annular members and cap are in predetermined 75 circumferentially relative positions.
- 75 10. The combination with a bottle or the like open at one end, of a cup shape bottle cap adapted to fit over said end so as to close the bottle, cooperating means on the cap and bottle for normally securing the cap on the bottle against removal unless access is had to the cap, cover means rotatably mounted on the cap and retained thereon by engagement with such cap for normally preventing access to the latter and including a removable part adapted when removed to allow access to the cap, and a lock rotatable with respect to the cover means for normally locking the removable part against removal.
- 80 11. The combination with a bottle or the like open at one end, of a cup shape bottle cap adapted to fit over said end so as to close the bottle, cooperating means on the cap and bottle for normally securing the cap on the bottle 85

means for rendering the indicia on the cap visible while still preventing access to the cap for releasing it from the bottle, said last mentioned means comprising an opening in the cover means and a glass insert in said opening.

5

14. The combination with a bottle or the like open at one end, of a cup shape bottle cap adapted to fit over said end so as to close the bottle, cooperating means on the cap and bottle for normally securing the cap on the bottle 10 against removal unless access is had to the cap, an annular member on the edge portion of the cap and having an inwardly directed flange projecting over the edge face of the cap, means holding said member against axial movement on the cap while permitting its rotation thereon, a second cup shape member enclosing the base portion of the cap and having its side wall disposed in partly telescopic relation to the side wall of the first member, combination locking means between the first and second members but concealed thereby for normally locking the second member to the first against relative axial movement while still allowing relative rotation thereof, combination locking means between the cap and second member but concealed thereby for normally locking the second member to the cap against relative axial movement while still allowing relative rotation thereof, both of said combination locking means being of such character that upon disposing the cap and first and second members in predetermined and relative circumferential positions, axial removal of the second member is permitted, external indicia on the first and second members for governing manipulation of the combination locking means between the members, similar indicia on the cap and on the second member for governing manipulation of the combination locking means between such parts, and a glass insert in the end wall of the second member for rendering the indicia on the cap visible. 15 20 25 30 35 40
